UNITED STATES PATENT OFFICE.

CHARLES Y. KNIGHT, OF CHICAGO, ILLINOIS, ASSIGNOR, BY MESNE ASSIGNMENTS, TO
KNIGHT AMERICAN PATENTS COMPANY, A CORPORATION OF DELAWARE.

INTERNAL-COMBUSTION ENGINE.

1,129,104.

Specification of Letters Patent. Patented Feb. 23, 1915.

Original application filed October 10, 1908, Serial No. 457,057. Divided and this application filed April 23, 1909. Serial No. 491,841.

To all whom it may concern:

Be it known that I, CHARLES Y. KNIGHT, a citizen of the United States of America, residing at 154 Lake street, Chicago, in the 5 county of Cook and State of Illinois, United States of America, have invented certain new and useful Improvements in Internal-Combustion Engines, of which the following is a full, clear, and exact specification.

10 My invention relates to internal combustion engines, and particularly to petrol engines and the like, which are required to run at high speeds, but the invention is not necessarily limited to high speed engines.

15 The improvement set forth and claimed in this application has more especial reference to means whereby the same port is utilized both for the intake and exhaust, and the application is a division of my pending application, Serial No. 457,057, filed 20 October 10th, 1908.

The invention has for its primary object to so construct the engine that the full area of inlet and exhaust can be obtained very 25 rapidly and a larger port area obtained than has been heretofore possible, so that the charge can be quickly taken into the cylinder and the exhaust products very quickly expelled.

30 Further objects of the invention will appear in the following specification read in the light of the accompanying drawings, forming a part thereof.

The invention consists of the novel combinations and features hereinafter more 35 fully described, shown in the drawings, and particularly pointed out in the claims.

In the said drawings Figure 1 is a vertical section through the cylinder of an engine 40 constructed in accordance with this invention with the ports open to exhaust. Fig. 2 is a section showing the ports open for admission of the mixture.

The invention is illustrated in connection 45 with the sleeve valve type of engine in which the means for controlling fluid admission to and exhaust from the combustion or explosion space of the engine embodies a pair of coaxial sleeves arranged coaxially with the 50 working piston and situated within a fixed cylinder. In the preferable form of the invention, these features are employed in conjunction with water cooling means for radiating the heat from these sliding sleeves

and associated parts, and the port which 55 constitutes both the inlet and exhaust port, as heretofore mentioned, is formed in one of these sleeves.

The invention is also shown in connection or association with a head which is preferably water cooled and projects from the main cylinder into the inner one of the said sliding sleeves for closing the end of the latter and also controlling the port therein during the compression and firing strokes 65 of the piston.

Describing the invention more in detail in connection with an engine of this type, it will be seen that I provide a cylinder *a* which is the fixed cylinder, having a surrounding water jacket *b* and oppositely disposed exhaust ports *c*. The upper part of the cylinder *a* is closed by the water cooled head *d* in which is formed a combustion chamber *e*. Suitable spring rings *p* are 70 provided to make tight joint between this cylinder head and the inner sleeve *h*, the position and function of which are well understood by those skilled in this art. An annular space *f* is left between the head 75 and the cylinder *a*, and into this project the upper ends of the two sleeves, the inner sleeve *h*, just referred to, and the outer sleeve *g*. These sleeves *g* *h* are arranged and slide concentrically within the main 80 cylinder *a* and are provided with ports *i*, *j*, respectively. The sleeves *g*, *h*, are operated in accordance with the four-stroke cycle by two eccentrics *k*, *l*, respectively, which are preferably placed 90 degrees. Rotation at 85 half the speed of the engine crank shaft is given to these eccentrics by any suitable means. The working piston *m* is placed within the inner sleeve *h*.

The upper end of the outside sleeve *g* 90 is formed with or carries an annular flange *g'* bearing against the inner side of the wall of the cylinder *a* and is provided with a peripheral piston ring *o*.

The intake port of the engine is shown at 100 *n* and is preferably so spaced from one of the exhaust ports *c* as to allow the annular flange *g'* to play up and down between the two ports *n* and *c* in such a way as to at one time direct the fluid admission from the intake port through the adjacent annular space between the head and the cylinder *a*, 105 and into the combustion space of the engine

via the port or ports of the inner sleeve, and at another time to cut off fluid admission from the intake port and open communication with the exhaust ports *c* through 5 the two ports *i*, *j*, in the sleeves when these two ports come into register. In order to insure against leakage, the flange *g'* may be provided with an ordinary piston ring *o* which bears against the face of the cylinder 10 wall *a*. The flange *g'* is annular in form and offset from the sleeves so as to form a by-pass for the passage of the fluid from the intake when the flange descends to a 15 position below the port in the inner sleeve, at which time it continues to intercept direct communication between the intake and exhaust ports.

In the operation of the engine, fluid admission, of course, takes place through the 20 intake port *n*, the mixture being drawn into the space *f* surrounding the head and into the sleeve *h* encompassing the combustion space of the engine through the ports *j* in the sleeve *h* when the sleeve *g* is in its lowest 25 position, as shown in Fig. 2. The ports *i* in the outer sleeve are adapted to register with the ports *j* in the inner sleeve *h* and with the exhaust ports *c* in the fixed cylinder when the sleeve *g* is in its upper position, as shown in Fig. 1, whereupon communication with the induction or intake 30 port *n* is cut off and communication between exhaust port or ports *c* and the explosion space is established directly through the 35 ports *i*, *j* in the sleeves.

In this construction, it will be seen, therefore, that the two sleeves in conjunction with the internal head *d*, the fixed cylinder and the annular flange *g'* constitute a means 40 for controlling fluid admission to and exhaust from the combustion space of the engine and by the employment of the port controlling provisions *g'* on the outer sleeve, I am enabled to utilize the whole available 45 port area of the inner sleeve for both fluid admission to and exhaust from the combustion space, and consequently it requires but a comparatively short movement of the sleeves to obtain an area of port opening 50 which is double that obtained with the ordinary sliding sleeve arrangement heretofore employed, and as a consequence, the possible speed of the engine is greatly increased, while the temperature of the upper portion 55 of the cylinder and sleeves is more easily kept uniform to guard against or prevent distortion and overheating at local points.

Having now described my invention, what I claim is:

60 1. An internal combustion engine having a combustion space and embodying in combination a cylinder provided with intake and exhaust ports, a slidable cylindrical element coaxial with the combustion space and 65 having a port, common to both intake and

exhaust, leading thereinto, means co-operating with said element and last said port for controlling fluid admission to and exhaust from the combustion space, embodying means for alternately connecting the last 70 said port with the intake and exhaust ports, a working piston in said combustion space, and means connecting the piston with the first said means.

2. An internal combustion engine having 75 a combustion space and embodying in combination a cylindrical element surrounding the combustion space and forming the side wall thereof and provided with a port common to both intake and exhaust, and means 80 operatively connected with the piston for alternately connecting the last said port with said exhaust port and intake port.

3. In an internal combustion engine, the combination of a fixed cylinder having intake and exhaust ports, two cylindrical elements telescoped one over the other within said cylinder and slidably with relation to one and another and to said cylinder, said cylindrical elements having ports adapted 90 to register for fluid admission to and exhaust from the inner one of said cylindrical elements, means fixed with relation to the said fixed cylinder and arranged coaxial with the inner one of said cylindrical elements for closing the end thereof, and with relation to which the said cylindrical elements reciprocate, port controlling provisions provided around one of said cylindrical elements for shutting off communication between said intake port of the fixed cylinder and the ports in the said cylindrical elements when the ports in the latter are in register with one another and with said exhaust port, and for shutting off communication between the port of the inner one of 100 said elements and the exhaust port of the fixed cylinder when the ports of said elements are out of register and the port of the inner one of said elements is out of lapped relation with the said means for closing its end.

4. An internal combustion engine having a combustion space and embodying in combination a fixed cylinder coaxial with the combustion space and having intake and exhaust ports, the engine embodying also a passage connecting the combustion space with both the said intake and exhaust ports, a crank shaft, a working piston operatively connected thereto and arranged in the combustion space coaxially therewith, means for controlling fluid admission to and exhaust from said combustion space, operatively connected with the piston and embodying two coaxial sleeves having ports adapted to register with one another and with said passage and port controlling provisions on one of said sleeves intercepting direct communication between said intake and exhaust 125 130

- ports and movable with relation to the port of one of said sleeves for alternately establishing communication between the last said port and the intake and exhaust ports.
5. An internal combustion engine having a combustion space and embodying in combination a fixed cylinder coaxial with the combustion space and having intake and exhaust ports, the engine embodying also a
- 10 passage connecting the combustion space with both the said intake and exhaust ports, a crank shaft, a working piston operatively connected therewith in the combustion space, means for controlling fluid admission
- 15 to and exhaust from the combustion space operatively connected with the piston and embodying a fixed head coaxial with said cylinder, a sleeve encompassing said head, a second sleeve encompassing said first sleeve
- 20 and slidable thereover, said sleeves having ports for admitting fluid to and exhausting fluid from said combustion space, and port controlling provisions on the outer one of said sleeves arranged in said passage and
- 25 intercepting direct communication between the intake and exhaust ports, and means operatively connecting said sleeves with said crank shaft for moving said port controlling provisions during a part of one revolution
- 30 of the crank shaft to a position to establish communication between the intake port and port of the inner sleeve and cut off communication between said ports and the exhaust port, and during another part of the revolution
- 35 of the crank shaft to cut off communication between said intake port and the port of the inner sleeve and establish communication between the last said port and the exhaust port.
- 40 6. An internal combustion engine having a combustion space and embodying in combination a fixed cylinder provided with intake and exhaust ports, a crank shaft, a working piston operatively connected there-
- 45 with and arranged in said combustion space, a head projecting into said cylinder and fixed with relation thereto, a sleeve slidable over said head, a second sleeve slidable over said first sleeve, said sleeves having ports
- 50 adapted to register and having their upper ends situated in the space between said head and the face of the fixed cylinder, and an annular flange on the outer one of said sleeves, situated in said space and inter-
- 55 cepting direct communication between said
- intake and exhaust ports and movable during a part of the revolution of the crank shaft to a position to establish communication between the intake port and the port of the inner sleeve and during another part of such revolution to a position to establish communication between the exhaust port and the port of the inner sleeve when the ports of the two sleeves come into register.
7. An internal combustion engine having a combustion space and embodying in combination a fixed cylinder provided with intake and exhaust ports, a crank shaft, a working piston operatively connected therewith and arranged in said combustion space, 70 a head fixed with relation to the cylinder and projecting thereinto and spaced from the walls thereof, a sleeve embracing and slidable over said head, a second sleeve embracing and slidable over said first sleeve, 75 said sleeves having ports adapted to register, a flange offset from and connected to the outer one of said sleeves and situated in the space between the head and cylinder and intercepting direct communication between said intake and exhaust ports, said flange being movable to a position below the port of the inner sleeve to establish communication between the latter port and the intake port, and movable to a position above 80 the port of the inner sleeve to establish communication between the last said port and the exhaust port, and means connecting said sleeves with the crank shaft.
8. An internal combustion engine having a combustion space and embodying a cylinder provided with intake and exhaust ports, a movable sleeve constituting a wall for the combustion space aforesaid provided with a port common to both the intake and the exhaust ports aforesaid, a port-controlling sleeve concentrically arranged with respect to the sleeve aforesaid embodying means for connecting the port of the wall of the combustion chamber alternately with the intake 95 and exhaust ports of the cylinder, a working piston in the combustion space, and means for connecting the piston with the port-controlling sleeve.
- In testimony whereof I affix my signature 100 in presence of two witnesses.
